[57] CLAIM

The ornamental design for a tie down eyelet, as shown and described.

DESCRIPTION

FIG. 1 is a front elevational view of a first embodiment of a tie down eyelet showing my new design, the rear elevational view being a mirror image;

FIG. 2 is a side elevational view thereof, the side opposite being a mirror image;

FIGS. 3 and 4 are respectively top and bottom plan views thereof;

FIG. 5 is a front elevational view of a second embodiment thereof; the rear elevational view being a mirror image;

FIG. 6 is a top plan view thereof, the bottom plan view being a mirror image.

The side elevational views of the second embodiment are substantially similar to FIG. 2.

The broken line showing of fastening means in FIG. 1 is for illustrative purposes only and forms no part of the claimed design.
